UNITED STATES PATENT OFFICE

2,466,870

APPARATUS FOR HEAT-TREATING STEEL

Arthur E. Twiehaus and Percy J. Wilton, Gary,
Ind., assignors to Carnegie-Illinois Steel Corporation,
a corporation of New Jersey

Application April 27, 1946, Serial No. 665,470

4 Claims. (Cl. 263—10)

1

This invention relates to an apparatus for thermally treating steel for the purpose of imparting to the metal advantageous cold-forming properties and particularly to apparatus for the thermal treatment of alloy steels to prevent the formation of banding and induce additional corollary improvements in the mechanical characteristics thereof.

Commercial experience has taught the steel industry several ways for suppressing banding tendencies of steel. Such procedures usually involve bringing all of the constituents of the steel into a solid solution, and then transforming the steel into the alpha state by cooling at a rate sufficiently rapid for preventing migration of respective constituents throughout corresponding grains. Quenching and tempering may be mentioned as examples of such procedures.

Quenching in water and tempering are a satisfactory procedure for preventing banding in steels in many instances, but fail to achieve the desired results when a final product is sought which is to have a maximum softness, particularly when high ductility requirements are equally present. These properties are associated conventionally with the spheroidized structure, specifically when the latter is achieved by straight annealing under the lower critical temperature. It has been found that the spheroidizing treatment of water-quenched steels has to be conducted at higher temperatures, which temperatures occasionally may convert the original martensitic areas into undesirable well-laminated pearlite in place of spheroidized cementite and partially restore its original banded structure.

The deleterious effect of banding and of changes in the properties of the metal induced by treatments resorted to for elimination of banding, is particularly noticeable in sheets and similar thin bodies of large dimensions during cold-forming operations to which they are subjected in the course of the usual manufacturing processes. There is not known any treatment industrially suitable for elimination of banding in sheets without undesirably affecting the properties of the metal treated.

Application of treatments found effective for banding elimination in bars and similar bodies, such as, for example, quenching followed by a tempering operation, is not feasible from the practical standpoint when applied to sheets, particularly during continuous operations. Two additional major obstacles have to be considered in this case, namely, excessive warping induced by immersion in liquid cooling media, and rust-

2

ing induced by the use of aqueous quenching baths.

The aforementioned obstacles have been met in steel plants making alloy steel sheets through a compromise consisting in the use of normalizing in place of quenching and drawing, at the cost of reduced mechanical properties and only a partial elimination of banding. In this method, strip or sheets were fed continuously into a normalizing furnace, confining a properly selected atmosphere for reducing surface oxidation. The material introduced is gradually heated to the temperature, or slightly below the temperature, of the hot zone of the furnace, usually ranging between 1700 deg. F. and 1750 deg. F., and then allowed to cool in the controlled atmosphere during the travel through cooler portions of the furnace to a temperature substantially preventive of surface oxidation of the sheets. Heat treated sheets are subjected to a spheroidizing anneal or used without this treatment, depending upon the requirements of the ultimate application. Spheroidizing annealing, when used, accentuated the degree of banding resulting from the primary treatment.

It has been found that the properties of steel can be improved greatly, particularly in respect to the yield point and banding removal, by increasing the cooling rate, after heating to the austenitizing temperature, above the rate required in normalizing, but below the rate induced by quenching in liquids.

After an extended investigation, it has been discovered that the cooling rate induced by the application of supersaturated vapors, exemplified by wet steam, to sheets heated to austenitizing temperature, induces a cooling rate that is optimum from the standpoint of banding elimination and mechanical properties produced, provided a proper control is exercised in steam application. Steam quenched sheets possess a higher yield point, a substantially greater freedom from banding than normalized stock, and have an unimpaired surface.

Our invention provides an apparatus for carrying out the above-outlined procedure in an effective manner without requiring extensive modifications of existing equipment.

The invention will be understood more readily by reference to the accompanying drawings, in which:

Figure 1 is a fragmentary side elevation of a furnace embodying the improved features of construction of the present invention;

Figure 2 is an enlarged longitudinal sectional

elevation of the quenching zone of the furnace of Figure 1;

Figure 3 is a fragmentary elevation of a stack removably disposable on the furnace showing details of the construction and mounting thereof, the view being taken at right angles to Figure 2, looking in the direction of the arrows and on the plane of line III—III of Figure 2;

Figure 4 is a plan view of the stack;

Figure 5 is a vertical section taken along the plane of line V—V of Figure 3, looking in the direction of the arrows;

Figure 6 is a plan view of steam injector pipes mounted in the furnace for quenching the heated steel passing through the furnace; and

Figure 7 is an end elevation of the quenching pipe assembly shown in Figure 6.

Referring more particularly to the drawings, reference character A represents a furnace having heating, quenching, and cooling zones, and containing power driven conveyor rolls B by which the plates to be treated are conveyed through the furnace. The furnace A is generally of a standard continuous heat treating type, but modified in a manner which permits a convenient conversion from a conventional operation to the operation of the present invention.

For this purpose, two sections of the furnace roof are removed, and replaced by a section of roof 9, corresponding to that marked "cooling or soaking zone" in Figure 2, and quenching assembly including a stack 11 and quenching heads 13 beyond the stack.

The stack 11 is a box open at the top and bottom designed to discharge hot gases issuing from the furnace, and to prevent them from flowing out into the space about the quenching heads 13. It is composed of end posts in the form of channels 15 and 17, the lower ends of which penetrate the sand filling 19 in sealing channels 21, 23 disposed at the sides of the furnace to prevent the escape of furnace gases. A front wall or plate 25 and a rear wall or plate 27 extend between the channels and are secured thereto. The front plate 25 terminates a short distance below the center of roof section 9 and defines an intake opening 29 for the entry of furnace gases into the stack, while the rear plate 27 extends downwardly to within a short distance of the conveyor. The stack is supported by clips 30 on plate 25 adapted to fit over supporting angles 31 on the roof of the furnace. A plate welded in the top of the stack has an eye 33 adapted to be engaged by a crane hook for lifting the stack out of the furnace to permit replacement of the removable roof section when it is desired to return to conventional operation.

The quenching heads 13 are more fully described and claimed in a copending application Serial No. 665,357, filed April 27, 1946, by Percy J. Wilton. They are composed of a pair of tubes 35 and 37, each closed at one end as indicated at 39, and provided with a plurality of holes 41 which are adapted to direct quenching steam onto the plate P being treated. A suitable number of the holes 41 is provided, depending upon the size of the furnace, sufficient for directing the steam uniformly over the plates P. The tubes 35 and 37 have their open ends tapered inwardly as indicated at 43, so that air is drawn thereinto through suitable inlets (not shown) and commingled with the steam supplied thereto, by venturi action, whereby the steam is condensed to a greater or less extent, as may be desired. Optimum results in treatment of the plates P are usually obtained

with saturated steam. The tubes 35, 37 are suspended from a beam in the form of a rod 45 extending through eyes 47 of straps 49 welded to the pipes 35, 37 transversely thereof. The rod 45 is carried by eye bolts 44 received in sockets 48 mounted in the furnace walls. This construction permits vertical adjustment of the tubes and also permits them to be readily removed for demounting when desired. Each of the eyes 47 is welded to its strap 49 and is provided with a set screw 51.

Preferably, the holes 41 are fitted with downwardly extending nozzles 53, and angularly disposed deflector plates 55 are provided to direct the resulting jets of steam onto the plates P being quenched, the angle of impingement being, in practice, about 60 deg.

From the foregoing, it will be evident that the stack, by natural draft, deflects upwardly the hot gases issuing from the furnace and prevents their interfering with the application of steam to the heated plates. As shown, the stack extends across the entire width of the furnace and the rear plate 27 extends within a short distance above the rolls B sufficient only to provide clearance 57 for passage of the plates.

The bottom 59 of the heat treating furnace A is shown as being provided with expansion joints 60, and the furnace is mounted on foundation blocks or beams 61.

It will be understood also that in addition to a vertical adjustment for proper application of steam to the plates P, the tubes 35 and 37 with their deflector plates 55, may be removed from the furnace as a unit and replaced at will. Likewise, the stack 11 may be lifted out of the furnace and replaced as desired. When the stack 11 and the spray pipe assembly are removed from the furnace, and the removed cover sections restored, the furnace is ready for conventional use.

In this connection, it may be pointed out that the distance from the heating zone of the furnace to the quenching tubes 35 and 37 must be such that the steel does not cool below the austenitizing temperature of the particular grade of steel being processed. This distance will be variable for any given grade of steel and may be taken care of by suitable variable positioning of the quenching jets relative to the heating zone, by providing additional sets of sockets.

While certain specific embodiments of the present invention have been described and illustrated as examples of one form of apparatus suitable for carrying out the invention, it will be understood that the apparatus is not limited rigidly to the specific details of the structure that have been herein illustrated and described, and it will be understood that it is intended and desired to embrace within the scope of this invention such modifications and changes as may be necessary to adapt it to varying conditions and uses, as set forth in the appended claims.

We claim:

1. In apparatus for heat-treating flat-rolled metal including a continuous furnace composed of spaced side walls, a roof extending therebetween having a removable section intermediate the ends of the furnace and a conveyor for moving therethrough the material to be treated, the improvement comprising a stack removably disposable transversely on said furnace at one side of the opening left by removal of said section, said stack having end posts spaced apart about the width of the furnace and front and rear plates extending therebetween providing a vertical duct open at the top and bottom, said rear plate hav-

ing its lower edge adjacent the conveyor to limit the escape of furnace gases into said opening but spaced from the conveyor sufficiently to afford clearance for said material.

2. In apparatus for heat-treating flat-rolled metal including a continuous furnace composed of spaced side walls, a roof extending therebetween having a removable section intermediate the ends of the furnace and a conveyor for moving therethrough the material to be treated, the improvement comprising a stack removably disposable transversely on said furnace at one side of the opening left by removal of said section, said stack being a box open at the bottom and top, having a length substantially equal to the width of the furnace, with front and rear side walls spaced along the conveyor, the rear side wall extending downwardly toward the conveyor farther than the front side wall.

3. In apparatus for heat-treating flat-rolled metal including a continuous furnace composed of spaced side walls, a roof extending therebetween having a removable section intermediate the ends of the furnace and a conveyor for moving therethrough the material to be treated, the improvement comprising a stack removably disposable transversely on said furnace at one side of the opening left by removal of said section, said stack being a box open at the bottom and top,

having a length substantially equal to the width of the furnace, with front and rear side walls spaced along the conveyor, said front side wall having supporting means thereon adapted to engage the portion of the roof adjoining said opening.

4. The apparatus defined by claim 1 characterized by sealing channels at the sides of the furnace, said posts extending downwardly into said channels.

ARTHUR E. TWIEHAUS.
PERCY J. WILTON.
